[57] CLAIM

The ornamental design for a font cartridge for computer output printers, as shown and described.

DESCRIPTION

FIG. 1 is a top plan view of a font cartridge for computer output printer showing our new design;

FIG. 2 is a bottom plan view thereof;

FIG. 3 is a front elevational view thereof;

FIG. 4 is a rear elevational view thereof;

FIG. 5 is a right side elevational view thereof; the left side being a mirror image thereof; and

FIG. 6 is a top, front and right side perspective view thereof on a reduced scale.

FIG. 1

FIG. 2

FIG. 3

FIG. 5

FIG. 4

FIG. 6
